Primary Examiner — Selina Sikder(74) *Attorney, Agent, or Firm* — Birch, Stewart, Kolasch & Birch, LLP(57) **CLAIM**

The ornamental design for an LED package body, as shown and described.

DESCRIPTION

FIG. 1 is a perspective view of a LED package body showing our new design;

FIG. 2 is a front view thereof where the rear view is a mirror image;

FIG. 3 is a left side view thereof where the right side view is a mirror image;

FIG. 4 is a top plan view thereof;

FIG. 5 is a bottom plan view thereof; and,

FIG. 6 is a cross-sectional view taken along, line 6-6 of FIG. 4.

The broken lines depict portions of the LED package body that form no part of the claimed design.

The cross sectional view shown in FIG. 6 is included for the purpose of showing the interior contours shown in FIG. 1 which may not be clear from the remaining illustrations. Any features of internal construction shown are incidental and form no part of the claimed design.
